UNITED STATES PATENT OFFICE.

OTTO J. DOERRE, OF CHICAGO, ILLINOIS.

DESIGN FOR A VENDING-MACHINE CASING.

Application filed January 10, 1925. Serial No. 11,992. Term of patent 7 years.

To all whom it may concern:

Be it known that I, OTTO J. DOERRE, a citizen of the United States, residing at Chicago, in the county of Cook and State of Illinois, have invented a new, original, and ornamental Design for a Vending-Machine Casing, of which the following is a specification, reference being had to the accompanying drawing, forming a part thereof.

The figure is a perspective view of a vending machine casing, showing my new design.

I claim:

The ornamental design for a vending machine casing, as shown.

OTTO J. DOERRE.
